UNITED STATES PATENT OFFICE.

F GORDON COBE, OF GREENVILLE, SOUTH CAROLINA.

DOBBY-LOOM.

1,383,076.

Specification of Letters Patent.

Patented June 28, 1921.

Application filed August 21, 1919. Serial No. 318,927.

To all whom it may concern:

Be it known that I, F GORDON COBB, a citizen of the United States of America, and a resident of Greenville, county of Greenville, and State of South Carolina, have invented certain new and useful Improvements in Dobby-Looms, of which the following is a full and clear specification.

My invention relates to looms and more particularly to multipliers. The main object of my invention is to render unnecessary the use in weaving certain classes of patterns of the long, heavy and cumbersome pattern-chains which have heretofore been generally employed. By the use of a multiplier, I can provide means for the weave of a special pattern which will appear in the cloth at regular intervals separated by the regular plain weave, without the use of the long pattern-chains which must include the pattern to be woven and patterns adapted to weave the plain cloth. A good example of this is the weaving of handkerchiefs which have a pattern or border separated by a strip of plain cloth. I accomplish this by providing a pattern-chain which, at predetermined intervals, may be set in motion and which at the completion of the pattern and at the time when the pattern has been woven will remain idle while the plain cloth is being woven, when it will again begin to operate to insert the pattern into the cloth.

Another object of my invention is to provide a pattern-chain mechanism which may be easily applied to the ordinary loom now in use without a re-arrangement of the mechanism of the ordinary loom.

A still further object is to arrange such mechanism so that it may be operated when desired, but, when it is necessary to weave just plain cloth, the pattern-chain will remain stationary indefinitely and the usual operation of the loom not be affected in any way.

A still further advantage of my invention is that the multiplier mechanism may be entirely removed and replaced when any part of the same become disarranged or worn.

With these objects in view, I will proceed to more specifically describe and show the invention in the specification and drawings annexed.

55 In the drawings—

Figure 1 is a perspective view of a por-

tion of the ordinary dobby loom showing my invention applied thereto;

Fig. 2 is a perspective view of a rear part of the ordinary loom showing the position 60 of my invention;

Fig. 3 is a detail sectional view on the line 3—3 of Fig. 2.

In the drawings, 1 indicates the ordinary dobby arch and 2 the rocker-arm journaled 65 at 3. Mounted on the rocker-arm 2 by means of a nut and bolt 4 and adapted to rock with said rocker-arm is an arm 5 slotted longitudinally as shown at 6. A ratchet-operating arm 7 carrying a dog 8 has a pivotal and sliding connection with the arm 5. 70 This connection is provided by a bolt 9 passing through the upper end of the arm 7 and through the slot 6 in the arm 5, which bolt is secured by a nut 10 on the other end 75 thereof. A second nut 11 (more clearly shown in Fig. 3) is placed on the bolt so as to clamp the arm 7 in any desired position in the slot 6 and at the same time allow it to have a pivotal movement on the bolt 9. 80

A ratchet-wheel 12 is mounted on a stud-shaft 13 on the frame of the loom. Cast integral with the wheel 12 is a sleeve 14 carrying a worm 15 made integral therewith so that wheel 12 and worm 15 will turn 85 simultaneously.

Removably secured to the dobby arch 1 by bolts 16 is a bracket 17. This bracket may be of any suitable design but is preferably as shown and comprises an upright arm 90 18 which lies against the dobby arch and is secured thereto by the screws 16 and extends outwardly at right angles thereto as at 19. Secured to the right angular portion and depending therefrom is a vertical portion 20 having made integral therewith bearings 21 and 22. Passing through the bearings 20 is a shaft 23 carrying at one end thereof a worm-wheel 24 adapted to mesh with the worm 15. Rigidly mounted on the 95 other end of the shaft 23 is a bevel-gear 25. A second shaft 26 is mounted at right angles to the shaft 23 and extends transversely of the loom and has one of its ends supported by the bearing 22 provided in the bracket 100 17. The other end of this shaft 26 is supported by a bearing-block 27 secured by a nut and bolt 28 to the frame portion of the loom. A second bevel gear 29 is rigidly secured on the end of the shaft 26 adjacent 105 the bevel-gear 25 and adapted to mesh therewith.

110

30 designates a disk provided with a collar 31 and set-screw 32, by means of which it is rigidly secured to the other end of the shaft 26. A pawl 33 is loosely mounted on the end of the shaft 26 with projections beyond the disk 30, and this pawl is held in place by a collar 34 secured to the shaft by a set-screw 35. A stud or pin 36 is provided on the disk 30 near the outer periphery 10 thereof and is adapted to engage the loosely-mounted pawl 33 to carry the same around its pivot when the disk 30 is rotated.

A bracket 37 mounted by a bolt 38 to the loom-frame pivotally supports an arm 39 by a bolt as at 40. Adjustably mounted on this arm 39 is a cam-plate 41. Adjustment is allowed to plate 41 by means of the bolts 42. By this arrangement, it is evident that the cam-plate 41 may be adjusted to any 20 desired position with respect to the arm 39.

A bracket 43 secured to the loom-frame by a bolt 44 supports one end of the actuator-lifting-arm 45. This lifting-arm 45 is pivotally mounted on the bracket 43 as at 46. A lug 47 is made integral with said arm 45 and is adapted to coöperate with supporting-lug 48 on the arm 39 to hold the arm 45 in its raised position. The arm 45 is bifurcated as at 49 to straddle the pattern-chain-actuator-arm 50. Thus it will be seen that when the lug 47 rests upon the lug 48, the forward end of the arm 45 will be kept in the position indicated in Fig. 1 of the drawings and will support the arm 50 in its raised or inoperative position. A spring 51 maintains the arm 39 in the position shown in Fig. 1, that is, in the position in which it supports the arm 45.

As in the ordinary looms now on the market, the arm 50 receives its reciprocating motion from the rocker-arm 2 and the dog 52 coöoperating with the ratchet 53 moves the pattern-chain 54 step by step to present the different patterns and through the usual mechanism to operate the harness and weave the patterns into the cloth. In the drawings, I have shown a loom in which there is an upper and lower lifter 55 and 56.

I will now describe the operation of my invention in so far as it controls the starting of the pattern-chain: The rocker-arm 2 during its rocking motion transmits to the arm 5 a similar rocking motion owing to the mounting of said arm 5 upon the rocker-arm 2. The ratchet-operating arm 7 will therefore receive a reciprocating motion and will actuate the ratchet-wheel 12. I control the distance the ratchet-wheel is moved each time by adjusting the arm 7 in the slot 6, 55 as will be readily understood. Upon each rocking motion of the arm 2 and the arm 5, the ratchet-wheel 12 will be turned a distance corresponding to the adjustment of the arm 7. A rotary motion, therefore, will 60 be transmitted to the worm 15 and, through

the worm-wheel 24, shaft 23 and bevel-gears 25 and 29 to the shaft 26, which will be rotated, of course, at a very much less speed than the ratchet-wheel 12 owing to the reduction which occurs through the train of 70 gears just described. The disk 30 is mounted rigidly to the shaft 26 and receives the rotary motion imparted thereto. Stud 36 will therefore be carried slowly around and will engage the dog 33 which also will be 75 carried around until it engages the cam-plate 41. By thus engaging this cam-plate a continued movement will swing the arm 39 by reason of the cam in the direction indicated by the arrow in Fig. 1. Thus it 80 will be seen that when the arm 39 is moved in the direction of the arrow, the lug 48 on the arm 39 will slip from under the lug 47 carried by the supporting arm 45 and allow this arm 45 to drop. The arm 50 being 85 supported by the arm 45 in a raised position will also fall and come into engagement with the ratchet 53, whereby the dog 52 on the arm 50 will actuate the ratchet and transmit a feeding motion to the pattern-chain, as in the usual way.

From this description, it will be seen that at any predetermined time, through the train of gears included in my invention, I may cause the arm 50 to drop into engagement with the ratchet 53 and thereby operate the pattern-chain. The pattern-chain will now be operated and insert the desired pattern into the weave of the cloth and the operation of such pattern-chain will continue until the same has made one complete revolution—that is, the pattern has been completed.

In order to disengage the dog 52 from the ratchet 53 and to restore the arm 45 to 105 its elevated position, I insert in the last pattern 57 of the pattern-chain 54 a pin 58. This pin 58 actuates the jack 59 which, through the spring 60, exerts a pull on the strap 61, which strap extends over the 110 sheaves 62 and from thence over a pulley 63 mounted on the loom-frame and secured to the arm 45 at 64. It will be understood that I may return the arm 45 to its raised position in any suitable manner; I have 115 shown the arrangement just described as embodying one of the numerous ways in which it may be done. Thus it will be seen that as the last pattern approaches and the pin 58 causes the jack 59 to operate, it will exert 120 a pull on the strap 61 and, as just described, raise the arm 45 and with it the arm 50 carrying the arm 50 out of engagement with the ratchet 53 and stopping the step-by-step motion of the pattern-chain. When the arm 125 45 is in its lower position, the face 65 of the lug 47 abuts the face 66 of the lug 48 so that when the arm 45 is again pulled upwardly the lug 48 will snap under the lug 47 by reason of the pull exerted by the 130

spring 51. When the lug resumes the position shown in Fig. 1, that is, under the lug 47, it is obvious that the arm 45 will be supported in its raised position and will remain 5 in such position until the disk 30 has again completed a revolution and carried the dog 33 around to again operate the arm 39 through the cam-plate 41.

In order to provide for plain weaving in 10 a dobby of this construction, I arrange the pins in the bar which carries the pin 58 in such manner that at each outward movement of the lifter which acts upon the lower side of the jack's alternate harness-frames— 15 as for instance one or more of the odd-numbered frames—shall be raised, while at each outward movement of the lifter which acts upon the upper series of the jacks, one or more of the remaining harness-frames— 20 for instance, the even-numbered ones—shall be raised. Therefore it will be seen that while the pattern-chain is inactive or stationary, the loom will weave plain cloth, which it may do indefinitely or until the 25 timing mechanism has again dropped the arm 45 and allowed the arm 50 to again operate the pattern-chain to insert a pattern in the weave of the cloth.

It is obvious that by adjusting the throw 30 of the ratchet-operating arm 7 by means of the bolt 9, I may cause it to operate 1, 2, 3, or 4 teeth as desired and thus cause the loom to weave any number of picks before the pattern is inserted again. This may also 35 be done by putting on different ratchets 12, worm-gears 24 or bevel-gears 25 and 29. I can therefore cause the pattern to repeat say in 625 picks or 180,000 picks, or whenever desired by merely adjusting the throw of the 40 ratchet-operating arm, ratchet, work-gear and bevel-gears. A mill often finds it desirable to measure off the cloth in various lengths, known as "cuts", generally 60 yards long. This can be easily accomplished by 45 this multiplier by merely adjusting the arm 7, ratchet, worm-gear and bevel-gears.

It should be noted that the device can be 50 easily removed from the loom by merely taking off brackets 17 and 37. It should also be noted that when it is desired to disconnect the multiplier indefinitely, this may 55 also be done in various ways, one way being by removing the ratchet-operating arm 7. In such case, the loom could then be used without the mechanism functioning in any manner.

The nature and scope of the invention having been thus indicated and its preferred embodiment having been specifically described, what is claimed as new is:

1. In a loom of the class described having a pattern-chain and a rocker-arm, a ratchet-wheel, means operable by said rocker-arm for rotating said ratchet-wheel, a shaft supported on said loom, a pawl

loosely mounted on one end of said shaft, connections between said ratchet-wheel and said shaft for rotating the shaft, means for operatively connecting said pawl to said shaft to rotate therewith, an actuator-arm 70 for actuating said pattern-chain, a lifting arm for supporting said actuator in its inactive position, means for maintaining said lifting arm in its raised position, and a cam on said last-mentioned arm coöperating with said 75 pawl to move said arm and allow said actuator-lifting-arm to drop and said actuator-arm to come into operative position to actuate the pattern chain.

2. In a loom of the class described having 80 a pattern-chain and a rocker-arm, a ratchet-wheel and adjustable means for rotating said ratchet-wheel, a shaft and a pawl loosely mounted on one end of said shaft, means between said ratchet-wheel and said shaft for 85 rotating the shaft, means coupled to said shaft for rotating said pawl therewith, actuating means for said pattern-chain, and means operable by said pawl to permit said pattern-chain-actuator means to engage in 90 an operative position.

3. In a loom, a rocker-arm, a pattern-chain mechanism, an actuator-arm operated by said rocker-arm for actuating said pattern-chain mechanism, a lifting means including a supporting means independent of the pattern-chain for retaining the actuator-arm from engagement with said pattern-chain mechanism, and a timing mechanism including a worm-gear drive for releasing 100 the supporting means to permit the actuator-arm to operate the pattern-chain mechanism.

4. In a loom, a rocker-arm, a pattern-chain mechanism, an actuator-arm operated by said rocker-arm for actuating said pattern-chain mechanism, a lifting means including a supporting means independent of the pattern-chain for supporting the actuator-arm from chain-operating position, a releasing means for said holding means, and 110 a timing mechanism including a worm-gear drive for operating said releasing means.

5. In a loom, a rocker arm, a pattern-chain mechanism, an actuator-arm operated by said rocker-arm for actuating said pattern-chain mechanism, a lifting means for displacing the actuator-arm from chain-operating position, a supporting means for said actuator-arm to retain it from chain-operating position, a releasing means for said 120 supporting means, and a timing mechanism including a worm-gear drive for operating said releasing means.

6. In a loom, a rocker-arm, a pattern-chain mechanism provided with a stop-pin, an 125 actuator-arm for said chain-mechanism, a lifting arm for the actuator-arm which is engaged therewith at one end and pivoted at its other end to the loom-frame and is adapted to lift the actuator-arm through mech- 130

anism operated by the movement of said stop-pin, a supporting means for the lifting arm normally retained in supporting position, a releasing means for the supporting means, and a timing mechanism for operating the releasing means.

7. In a loom, a rocker-arm, a pattern-chain mechanism provided with a stop-pin, an actuator-arm for said chain mechanism, a lifting arm for the actuator-arm which is engaged therewith at one end and pivoted at its other end to the loom-frame and is adapted to lift the actuator-arm through mechanism operated by the movement of said stop-pin, a supporting means for the lifting arm normally retained in supporting position and comprising a lug on the lifting arm and an arm pivoted at one end to the loom-frame and provided with a lug adjacent its free end for engaging beneath the lug on the lifting arm, a releasing means for the supporting means, and a timing mechanism for operating the releasing means.

8. In a loom, a rocker-arm, a pattern-chain mechanism provided with a stop-pin, an actuator-arm for said chain mechanism, a lifting arm for the actuator-arm which is engaged therewith at one end and pivoted at its other end to the loom-frame and is adapted to lift the actuator-arm through mechanism operated by the movement of said stop-pin, a supporting means for the lifting arm normally retained in supporting position and provided with a cam-plate, a releasing means for the supporting means comprising a rotating disk having a pin projecting from one face thereof and a loosely-mounted pawl which is rotated on the disk-supporting-shaft and adapted to engage said cam-plate to release the supporting means from the lifting arm, and a timing mechanism for operating the releasing means.

In testimony whereof I hereunto affix my signature.

F GORDON COBB.
